(57) **CLAIM**

The ornamental design for a vibrating device for pushchairs, as shown and described.

DESCRIPTION

FIG. 1 is a top perspective view of a vibrating device for pushchairs, showing our new design;

FIG. 2 is a bottom perspective view thereof;

FIG. 3 is a right side view thereof;

FIG. 4 is a left side view thereof;

FIG. 5 is a front view thereof;

FIG. 6 is a back view thereof;

FIG. 7 is a top view thereof; and,

FIG. 8 is a bottom view thereof.

The broken lines shown in the drawings are included for the purpose of illustrating environmental structure and form no part of the claimed design.
